US0D1047604S

(12) **United States Design Patent** (10) Patent No.: **US D1,047,604 S**
(45) Date of Patent: ** Oct. 22, 2024

(54) **PLASTIC PLATE**

(71) Applicant: **Zhejiang Enjoy & Wonderful Inc.**,
Zhejiang (CN)

(72) Inventor: **Yiwei Zhang**, Zhejiang (CN)

(**) Term: **15 Years**

(21) Appl. No.: **29/938,083**

(22) Filed: **Apr. 18, 2024**

(51) LOC (14) Cl. **07-01**

(52) U.S. Cl.

USPC **D7/584**; D7/566

(58) **Field of Classification Search**

USPC D7/587, 584, 566, 500, 510

CPC A47G 19/02; A47G 19/00

See application file for complete search history.
